GRAB BAR

Raymond U. H. Tegner, Lodi, Wis., assignor to
Amerock Corporation, Rockford, Ill.

Original design application Dec. 6, 1972, Ser. No.
312,781. Divided and this application Oct. 24,
1973, Ser. No. 409,325

Term of patent 14 years

Int. Cl. D8—06

U.S. Cl. D8—166

FIG. 1

FIG. 2

FIG. 3

FIG. 4

FIG. 5

FIG. 1 is a front view of a grab bar showing my new design.

FIG. 2 is a bottom view of the grab bar.

FIG. 3 is an end view.

FIG. 4 is an enlarged fragmentary sectional view taken along the line 4—4 in FIG. 1.

FIG. 5 is an enlarged sectional view taken along the line 5—5 in FIG. 2.

This application is a division of my co-pending application Ser. No. 312,781, filed Dec. 6, 1972.

I claim:

The ornamental design for a grab bar, as shown.
